UNITED STATES PATENT OFFICE.

RITCHARD T. RANDALL, OF MILL SPRINGS, MISSOURI.

RERAILER.

1,262,560.

Specification of Letters Patent.

Patented Apr. 9, 1918.

Application filed January 25, 1918. Serial No. 213,743.

To all whom it may concern:

Be it known that I, RITCHARD T. RANDALL, a citizen of the United States, residing at Mill Springs, in the county of Wayne and State of Missouri, have invented new and useful Improvements in Rerailers, of which the following is a specification.

This invention has reference to railway rolling stock, and has for its object to produce an extremely simple, cheap and thoroughly effective means whereby a derailed car may be easily and quickly guided again upon the rails of a track.

Other objects and advantages will appear as the nature of the invention is more fully understood, reference being had to the accompanying drawings, in which,

Figure 1 is a plan view illustrating the application of the improvement.

Fig. 2 is a similar view showing the manner in which a car derailed to the opposite side of a track upon which the device is illustrated as in Fig. 1, may be directed upon the track.

Fig. 3 is a side elevation looking toward the device as illustrated in Fig. 1.

Fig. 4 is a perspective view of the lower ing block.

Fig. 5 is a perspective view of the guide employed in connection with the block.

Fig. 6 is a sectional view approximately on the line 6-6 of Fig. 1.

Fig. 7 is a sectional view approximately on the line 7-7 of Fig. 6.

In the drawings, the ties of the railway track are indicated by the numerals 8 and rails, secured upon the said ties by the numerals 9.

It is to be understood that right and left hand blocks are employed with my improvement, the same, however, are identical in construction, but one of the blocks is arranged to be received upon the left hand side of the track as indicated in Fig. 1, while

the other block is shaped to be arranged upon the right hand side of the track as indicated in Fig. 2. Each of the blocks is, therefore, indicated by the numeral 10, and each comprises a member constructed to

form two sides 11 and 12 respectively, each of the said sides having its lower edge provided with an outstanding flange 13 forming the base for the block. The sides are connected by a web 14 which has its under

face horizontally straight and the lower wall of the said web is in a line with the under

face of the heads 15 and 16 formed on the respective sides 11 and 12. The web 14 has its upper face arranged at an upward inclination or the same is rounded upwardly 60 from the beveled or inclined ends 17 and 18 of the heads 15 and 16 respectively. The web 14 is continued a suitable distance below the head 15, extending outwardly from the head as indicated by the numeral 19. 65 The head 16 is horizontally straight throughout the length thereof, but the head 15 is rounded from the inner to the outer end thereof.

By reference to the drawings, it will be 70 noted that the head 15 terminates approximately centrally of the head 16, and also by reference to the said drawings it will be seen that the wide extension 19 is formed 75 upon the side 12 as well as being connected with or formed on the inner face or side of the head 15. The side 16, at what I have termed the inner edge thereof, is, upon its inner face beveled as at 20, providing an angular pocket between the said end of the 80 side 11 and the rail 9 upon which the block is arranged. The sides 11 and 12 are spaced a distance approximately equaling the thickness of the head of the rails 9, so that the inner edges of the heads 15 and 16 will 85 rest directly upon the heads or ball of the said rail.

I employ both an inner and an outer re-railing rail indicated by the numerals 21 and 22 respectively. Both of these rails are 90 inclined downward from their inner to their outer ends, as shown in Figs. 3 and 5, and both of the said rails have their inner ends cut at opposite inclinations as indicated by the numerals 23 and 24 respectively. One 95 of the inclined ends of the rail 21 is designed to rest against the inner face of one of the track rails 9, as clearly illustrated in Figs. 1 and 2 of the drawings, and preferably the rail 21 at the outer end thereof is provided 100 with a spur 25 which is designed to enter one of the ties 8 and serves as a pivot point, whereby the rail 20 may be swung in proper engagement with the side of the track rail 9. The re-railing rail 22 has its head cut 105 away at its inner end as indicated by the numeral 26 so that the oppositely beveled sides of the said end may be received in the angular pocket provided between the side member 11 of the block 10 and the outer 110 side of the track rail 9.

It is believed from the foregoing descrip-

tion when taken in connection with the drawings, that the simplicity and advantages as well as the operation of the device will be perfectly apparent to those skilled in the art to which such inventions appertain, the derailed car wheels being arranged to travel over the re-railing car rails 21 and 22 so that the flanges of one of the wheels may be directed by the rerailing rail 21 against the inner face of the head of one of the track rails 9, and the bearing surface of the said wheel positioned upon the said track. In a like manner, the flanges of the opposite wheels will be directed by the re-railing rail 22 causing the flanges of the said wheels to pass between the inclined confronting ends of the heads 15 and 16 of the block 10, over the web 14 and following the contour from the inner end and inner face of the head 16 of said wheels will travel over the extension 19 and over the rounded tread surface of the head 16 on to the second track rail 9.

Having thus described the invention, what I claim is:

1. In a rerailing device for railroad rolling stock, a block, said block comprising spaced sides each provided with a head, and designed to be arranged over one of the track rails, one of said heads having a straight bearing surface, the other head having its bearing surface rounded from its inner to its outer end and its said inner end terminating inwardly of the outer end of the first mentioned head, both of the heads having their confronting faces arranged at a similar angle, a web connecting the angular ends of the heads below the tread surface of the heads, a latch on the side of one of the heads forming a continuation of the web, and rerailing rails each having its inner end arranged at an angle whereby one of the said rails may be positioned against one of the track rails, and the other rerailing rail 45 may be positioned between the sides of the block at the inner end of one of the said sides.
2. In a car replacer, a rerailing block comprising a member including a member channeled longitudinally from the under face thereof to provide two spaced sides and a

head for each of the sides, and the channeled portion of the block designed to be received over a rail, each of the heads terminating approximately equi-distant from the center of the block and having their confronting sides inclined in the same direction, a horizontally straight web connecting the heads at the said inclined portions thereof, one of the sides having its inner end beveled to provide a pocket between the same and the side of the rail, and rerailing rails, one of which being pivotally connected to one of the ties and the other having a reduced end received in the referred to pocket.

3. In a car replacing device, a block which is channeled longitudinally from its under face to provide two spaced sides, the inner corners of which are depressed longitudinally and the outer corners of which are flanged outwardly whereby the block may be arranged over a rail to rest on the base flanges thereof and on the ties supporting the rail, each of the sides being formed with an inwardly flanged head, one of the heads presenting a straight surface and the other head being rounded from its inner to its outer end, each of the heads terminating approximately equi-distant from the center of the block, said heads, at the confronting portions thereof being inclined in the same direction, a horizontally straight web connecting the said heads at the beveled portions thereof, a flange providing an extension for the said web on the inner face of the rounded head, the side having the rounded head having its inner edge beveled providing a pocket between the said side and one of the sides of the rail, rerailing rails each comprising a member inclined from its inner to its outer end and its inner end beveled in opposite directions whereby to contact with the sides of the rails and be arranged at an angle with respect to the said main rails, one of said rerailing blocks having its inner end reduced whereby to be received in the referred to pocket, and a pivot member securing the other rail to one of the ties.

In testimony whereof I affix my signature.

RITCHARD T. RANDALL.
